UNITED STATES PATENT OFFICE.

FRANK KINZBACH, OF HOUSTON, TEXAS.

WHIP STOCK.

Application filed October 26, 1925. Serial No. 64,851.

This invention relates to new and useful improvements in a whip stock.

One object of the invention is to provide a whip stock formed of sections hinged together.

In drilling wells it often becomes necessary to side track, that is to cut through the side of the casing in the bore and continue on down in a new hole. In order to do this 10 it is common practice to drop a whip stock down into the bore, which forms a deflecting guide for a milling cutter used to cut laterally through the casing.

The type of whip stock commonly used 15 consists of a cylindrical body whose upper end is beveled off on a long taper, said tapering end forming a wedge like deflector for the milling cutter which forces said cutter laterally against the casing to be perforated, 20 and as said cutter is rotated and moves downwardly it will cut a long vertical hole through the casing through which the drilling tool may work in the formation of a new bore.

25 In case the casing is crooked it often happens that the upper beveled end of the ordinary whip stock will stand out from the casing and will not give room enough for the cutter to wedge in between it and the casing.

30 The whip stock herein described is formed of sections hinged together so that the upper end thereof may lie back closely alongside the casing irrespective of the contour of said casing in the bore.

35 With the above and other objects in view this invention has particular relation to certain novel features of construction, operation, and arrangement of parts, an example of which is given in this specification and 40 illustrated in the accompanying drawings, wherein:—

Figure 1 shows a fragmentary side view of the whip stock as located in a casing.

45 Figure 2 shows a side view of the lower end of the whip stock located in the casing.

Figure 3 shows a fragmentary front elevation of the whip stock, and

50 Figure 4 shows a cross sectional view taken on the line 4—4 of Figure 3.

In the drawings the numeral 1 designates a casing set in a well bore. Sometimes the bottom of the bore is obstructed by the dropping of a bit, or tool, therein, or otherwise so that drilling in the old bore cannot be con- 55 tinued and an opening must be cut through

the side of the casing and drilling continued through said opening and a new bore thereby continued on down. In order to side track as above explained, a whip stock is dropped down into the casing and a milling cutter employed to so perforate the casing. As shown the whip stock includes a cylindrical body 2 whose lower end may be sharpened, as at 3, forming a guide and this lower end will wedge in the upper end of a 60 lower reduced section, as 4, of the casing, or rest on the bottom of the bore. The upper end of the whip stock is beveled one way on a long taper forming a sloping face as 5.

This face may be provided with an upwardly inclined recess 6 to receive a hook on the lower end of a cable by means of which the whip stock is let down into the casing. Ordinarily the back side of the whip stock, opposite the face 5, will lie 70 closely against the casing wall, particularly if the casing is straight. If the casing is crooked it often happens that the upper end of a one piece whip stock will stand away from the casing wall so that the milling 75 tool 7 will ride on the said upper end. In the present form the upper end of the whip stock is hinged to the main body, the axis of the hinge 8 being substantially parallel with the plane of the face 5. This hinge 80 will permit said upper end to lie back closely against the casing wall irrespective of the course of the casing.

What I claim is:—

1. A whip stock having a beveled upper 90 end hinged to the main body thereof.
2. A whip stock formed of a plurality of sections hinged together.
3. A whip stock having a body whose upper end is beveled on one side and jointed. 95
4. A whip stock formed of an upper section and a lower section, said sections being jointed together, the upper section having a face inclined to the longitudinal axis of the whip stock. 100
5. A whip stock formed with a lower cylindrical section and an upper section hinged to the lower section the upper end of the whip stock being beveled forming a lateral face inclined to the longitudinal axis of the 105 whip stock.

In testimony whereof I have signed my name to this specification.

FRANK KINZBACH.
